LAWN SPRINKLER

John D. Beinert, Babylon, N.Y., assignor to Melnor Industries, Inc., Moonachie, N.J., a corporation of New York

Filed Aug. 18, 1960, Ser. No. 61,817

Term of patent 7 years

(Cl. D91—1)

FIG. 1 is a perspective view of a lawn sprinkler showing my new design;

FIG. 2 is an enlarged top plan view thereof with the base omitted for convenience of illustration;

FIG. 3 is a side elevational view thereof as shown in FIG. 2; and

FIG. 4 is a side elevational view thereof taken from the left hand side of FIG. 2.

The dominant feature of my design reside in the portions shown in full lines.

I claim:

The ornamental design for a lawn sprinkler, as shown and described.
